UNITED STATES PATENT OFFICE

142,264

DESIGN FOR A SIDE HANDLE OR LIFT FOR COOKING VESSELS AND THE LIKE

Alfred F. Ramsthal, West Bend, Wis., assignor to
West Bend Aluminum Company, West Bend,
Wis., a corporation of Wisconsin

Application May 21, 1945, Serial No. 119,650

Term of patent 14 years

(Cl. D44—29)

To all whom it may concern:

Be it known that I, Alfred F. Ramsthal, a citizen of the United States, residing at West Bend, in the county of Washington and State of Wisconsin, have invented a new, original, and ornamental Design for a Side Handle or Lift for Cooking Vessels and the like, of which the following is a specification, reference being had to the accompanying drawing forming a part thereof, and in which:

Figure 1 is a top plan view, Figure 2 a front elevation, and Figure 3 an end elevation of a

cooking vessel side handle or lift showing my new design;

Figure 4 is a sectional view taken on line 4—4 of Figure 1;

Figure 5 is a sectional view taken on line 5—5 of Figure 1; and

Figure 6 is a sectional view taken on line 6—6 of Figure 1.

I claim:

The ornamental design for a side handle or lift for cooking vessels and the like, as shown.

ALFRED F. RAMSTHAL.
